UNITED STATES PATENT OFFICE

2,481,961

HEATING AND HARDENING BURNER.

Bert G. Ward, Jr., Chicago, Ill., assignor to National Cylinder Gas Company, Chicago, Ill., a corporation of Delaware

Application April 7, 1945, Serial No. 587,146

5 Claims. (Cl. 158—27.4)

1

This invention relates to blowpipes of that type in which there are provided a plurality of gas outlets usually arranged in a row so as to produce a sheet-like flame for application to, and relative movement in respect to and along, a surface to be treated. The gases include a suitable combustible gas and a suitable combustion supporting gas, these being hereinafter referred to as acetylene and oxygen without intention of limiting the invention to the use of these particular gases.

Apparatus of this type may be used for a wide variety of purposes, such as flame hardening, heating, softening, tempering, annealing, descaling, etc.

In apparatus of this type it has been proposed to form the body portion of the burner nozzle or torch tip from a single block of metal with holes bored therein or therethrough for the passage of the gases to form the plurality of flames arranged in a row, and for the circulation of a cooling fluid, such as water, to prevent the apparatus from becoming overheated during use.

As important features of a construction embodying the present invention, there are separate mixing passages for the gases supplied for each tip orifice, and disposed within the body of the torch tip; all of the gas ports and passages are so arranged that they may be readily cleaned for the removal of collected carbon or other material which might tend to clog them or reduce the gas flow therethrough; the gas passages leading from the point of mixture to the point of discharge are of such length as to afford ample time for the gases to become properly mixed before exit from the burner port; and the passages for cooling fluid are arranged adjacent to the surface of the burner from which the mixed gases exit, and therefore nearest to the flames and the surface of the article or part to be treated, whereby said cooling fluid more effectively removes heat from the torch tip and prevents overheating of the gas mixture before reaching the gas outlets.

My invention may be embodied in a torch tip so constructed as to incorporate all or only certain ones of the features above referred to.

In the construction illustrated, and in which all of said features are incorporated:

Fig. 1 is a side elevation of an apparatus embodying the present invention.

Fig. 2 is a top plan view of the blowpipe tip or burner body; the pipe connections thereto being removed; and certain passages being shown in dotted lines.

2

Fig. 3 is a side elevation of the part shown in Fig. 2.

Figs. 4 to 10 inclusive are transverse sections on the lines 4—4, 5—5, 6—6, 7—7, 8—8, 9—9, and 10—10 respectively of Fig. 3.

Fig. 11 is a phantom view in perspective showing in solid lines, only the cooling passages, and Fig. 12 is a phantom view similar to Fig. 11, but showing, in solid lines, only the gas passages.

In the construction illustrated the tip or burner body 20 may be secured by a brazed collar 22 to any type of handle 21, which is preferably of tubular form, and through which extends the conduit 23 for the oxygen, the conduit 24 for the acetylene, and a conduit 25 for the supply of a suitable cooling liquid which will be referred to hereinafter as water, but other fluids might be used. The tubular handle itself serves for the return of the cooling fluid.

So far as concerns this handle construction, it may be of well known type; and as will be understood, the conduits, preferably adjacent to the outer end of the handle, are provided with suitable coupling connections and control valves, likewise of standard form and not illustrated.

The main features of the invention are incorporated in the tip or burner body 20. This may be of a single piece of brass, or any non-ferrous metal, steel or alloy which does not oxidize when subjected to high temperature and is shown as being hexagonal in cross-section, and extending transversely to the general direction of the length of the handle. Within this body there are bored a plurality of passageways for the various fluids.

The passages for the flow of the water may be more readily visualized from Fig. 11. The end of the water supply pipe 25 is connected to a short passage 26 in the face A of the body, and the water flows therefrom through the passages 27, 28, 29, 30, 31, 32 and 33 to an outlet passage 34 which opens into the tubular handle 21. Each of the passages 26 to 34 inclusive may be bored into the body to the required distance, but not entirely to the opposite face, and the outer end of each passage other than passages 27 and 33 may be closed by a suitable plug. For instance plugs

35 shown in Fig. 4 close the upper ends of the passages 28 and 32. Plugs 36 close the outer ends of the passages 27 and 33; plugs 31 close the ends of passages 29 and 31, and plug 37' closes the end of passage 30. The passage sections 29 and 31 are disposed substantially parallel to and closely adjacent to the lower face B of the block, and extend substantially the full length of the

burner body, so that this face which is exposed to the highest heat, is most effectively cooled.

The passages for the acetylene and oxygen may be readily visualized from Fig. 12. The acetylene supply pipe 24 is connected to a short vertical passage 38 which connects with a passage 39 near the top surface A of the body and extending toward the opposite end of the body from that toward which the cooling fluid passages 27 and 33 extend. The acetylene flows from the passage 39 down through a short passage 40 to a passage section 41 extending at one side of the medial plane, and substantially the full length of the body, and disposed adjacent to one of the upper outer sides of the body.

The oxygen supply pipe 23 connects with a short passage 42 leading into the top face A of the block and connected to a passage 43 extending substantially parallel to the passage 39. This passage 43 connects with a short vertical passage 44 leading to a passage 45 extending in the medial plane of the body, substantially the full length of the block, and parallel to the passage section 41. The oxygen and acetylene passages 45 and 41 are toward the upper side of the body.

All of the gas passages 39, 40, 41, 43, 44 and 45 have their outer ends closed by suitable plugs. The ends of the passages 39 and 43 are closed by plugs 49, the upper ends of the passages 40 and 44 are closed by plugs 48, and the ends of passages 41 and 45 are closed by screw-in plugs 51.

For forming the series of flames, a plurality of passages 46 extend from the face B of the block to the passage section 45, and a series of diagonal passages 47 lead from the passage section 41 to each one of these passages 46, as shown particularly in Fig. 5. The passages 47 from the acetylene passage section 41 intersect the oxygen passages 45 in approximately the medial plane of the body, and at approximately the center line of the body, which is at some distance from the lower outlet ends of the passages 46. Thus the upper part of each passage 46 delivers oxygen, and the lower part from the point 50 of intersection with the passage 47 serves for the delivery of the gas mixture. Thus there is adequate time for the acetylene and the oxygen to become mixed during the flow from the intersection points 50 to the outlet ends of the passages 46. As these passages 46 and 47 are very small, the danger of flash back in any of them is comparatively slight. The passages 46 for the mixed oxygen and acetylene extend downwardly between the two cooling fluid passages 31 and 29 so that the mixed gases are kept reasonably cool prior to the escape at the surface B and the formation of the series of closely spaced flames which may merge as a single narrow sheet or ribbon flame.

The gas main passages 41 and 45 are preferably tapered from the supply passages 40 and 41 shown at the left end of Fig. 12 toward the opposite end so as to maintain uniform gas pressure throughout their lengths. They may be readily cleaned by unscrewing the plugs 51, and the passages 47 may be cleaned by unscrewing plugs 52. The passages 46 may be readily cleaned as they open directly to the atmosphere at their lower ends. As the gases are mixed at points well within the body of the burner, it will be obvious that if the face A of the burner body, which is subjected to high heat, becomes corroded, it will not effect the proper mixing of the gas for the flame. As all of the oxygen and acetylene passages 46 and 47 lead from very much larger passages 45 and 41, equal volumes of gas will flow to the mix-

ing points 50, and all of the long row of flames will be uniform. The flames will be simultaneously regulated by the usual control valves in the oxygen and acetylene supply pipes 23 and 24.

Having thus described my invention what I claim as new and desire to secure by Letters Patent is:

1. A burner body comprising a metal block having opposed side faces, top and bottom faces and end faces, the top face having inlets for fuel gas, oxygen and water, and an outlet for the water, all grouped approximately midway between the ends of the top face, a fuel gas passage and an oxygen passage each extending substantially the full length of said block adjacent to the top face, a row of gas mixture outlet passages leading to said bottom face and each having a branch leading to said fuel gas passage and a branch leading to said oxygen passage, a pair of water passages adjacent to said bottom face and upon opposite sides of said outlet passages, means connecting said water passages in series to said water inlet and said water outlet, and means connecting said oxygen and fuel passages in parallel to said oxygen and fuel gas inlets.

2. A burner body comprising a metal block having opposed side faces, top and bottom faces and end faces, the top face having inlets for fuel gas, oxygen and water, and an outlet for the water, a fuel gas passage and an oxygen passage each extending lengthwise of said block adjacent to the top face and connected to the corresponding inlet on said top face, a row of gas mixture outlet passages leading to said bottom face and each having a branch leading to said fuel gas passage and a branch leading to said oxygen passage, a pair of water passages adjacent to said bottom face and upon opposite sides of said outlet passages, means connecting said water passages in series to said water inlet and said water outlet, and means connecting said oxygen and fuel gas passages in parallel to said oxygen and fuel gas inlets.

3. A burner body comprising a metal block having opposed side faces, top and bottom faces and end faces, the top face having inlets for fuel gas, oxygen and water, and an outlet for the water, all grouped approximately midway between the ends of the top face, a fuel gas passage and an oxygen passage each extending substantially the full length of said block adjacent to the top face, a row of gas mixture outlet passages leading to said bottom face and each having a branch leading to said fuel gas passage and a branch leading to said oxygen passage, a passage for conducting cooling water from said water inlet to said water outlet, said passage having sections adjacent to and lengthwise of said bottom face and on opposite sides of said gas mixture outlets, a connecting section adjacent to one end face, and supply and return sections leading from the other ends to said water inlet and water outlet respectively.

4. A burner body comprising a metal block having opposed side faces, top and bottom faces and end faces, separate inlets for fuel gas, oxygen and water, and an outlet for the water, a fuel gas passage and an oxygen passage each extending substantially the full length of said block adjacent to the top face, a row of gas mixture outlet passages leading to said bottom face and each having a branch leading to said fuel gas passage and a branch leading to said oxygen passage, a passage for conducting cooling water from said water inlet to said water outlet, said passage having sections adjacent to and lengthwise of said bottom face and on opposite sides of said

gas mixture outlets, and a connecting section adjacent to one end face.

5. A burner body comprising a metal block having opposed side faces, top and bottom faces and end faces, the top face having inlets for fuel gas, oxygen and water, and an outlet for the water, all grouped approximately midway between the ends of the top face, a fuel gas passage and an oxygen passage each extending substantially the full length of said block adjacent to the top face and connected to its respective inlet, a row of gas mixture outlet passages leading to said bottom face and each having a branch leading to said fuel gas passage and a branch leading to said oxygen passage, a passage for cooling fluid leading from said water inlet nearly to one face, then downwardly nearly to said bottom face, thence lengthwise of the latter along one side of said gas mixture outlets nearly to the other face, thence transversely of said block, thence lengthwise nearly to the opposite end and along the other

side of said gas mixture outlets, thence upwardly nearly to said top face, and thence to said water outlet.
